BRAKE

Filed Dec. 3, 1927

FIG. 1

FIG. 2

INVENTOR
LUDGER E. LABRIE
BY
J. W. McConkey
ATTORNEY

UNITED STATES PATENT OFFICE

LUDGER E. LA BRIE, OF SOUTH BEND, INDIANA, ASSIGNOR TO BENDIX BRAKE COMPANY, OF SOUTH BEND, INDIANA, A CORPORATION OF ILLINOIS

BRAKE

Application filed December 3, 1927. Serial No. 237,375.

This invention relates to brakes and is illustrated as embodied in an internal expanding brake for an automobile. An object of the invention is to provide a very effective brake which can be manufactured inexpensively.

Various features of novelty relate to the anchoring of the brake on a pair of devices arranged in a novel manner on opposite sides 10 of the cam or its equivalent, and which also serve to hold a supporting bracket for the cam shaft, to various features of construction of the brake shoes, to a novel positioning device for the shoes, and to other desirable 15 details of construction which will be apparent from the following description of one illustrative embodiment shown in the accompanying drawing, in which:

Figure 1 is a vertical section through the 20 brake, just inside the head of the brake drum, and showing the brake shoes in side elevation;

Figure 2 is a partial horizontal section on the line 2—2 of Figure 1 and showing the 25 anchorage of the brake; and

Figure 3 is a partial vertical section through the brake operating means on the line 3—3 of Figures 1 or 2.

In the illustrated arrangement the brake 30 includes a rotatable drum 10, at the open side of which is arranged a stationary support such as a backing plate 12, and within which is arranged the friction means of the brake, which in this instance includes two 35 novel brake shoes 14 connected by an adjustable floating joint 16. The shoes 14 are forced apart to apply the brake, against the resistance of a return spring 18, by means such as a floating cam 20 extended downwardly to form an operating arm secured by 40 a pivot 22 to an arm 24 on a cam shaft 26 operated by a lever 28. The shaft 26 is journaled in a bearing formed by drawing tubular extensions on two stampings 30 and 32 45 which are welded or otherwise secured to two plates 34 arranged on opposite sides of the backing plate 12.

According to one feature of the invention, 50 the plates 34 forming the bracket for the cam shaft 26 are secured to the backing plate 12

by devices such as posts 36 having collars 38 engaging the inner plate 34 and having threaded on their outer ends clamping nuts 40 seated against the outer plate 34, the devices 36 being extended through slots formed 55 in the shoes 14 so that one of them serves as the anchor for both of the shoes when the drum is turning clockwise and the other one serves as the anchor when the drum is turning counterclockwise. The devices 36 are 60 provided with washers 42 seated against the collars 38 and co-operating with washers 44 engaging the outer sides of the shoes and held by cotter pins 46 to confine the shoe against lateral movement and guide them in 65 their brake-applying movements.

One of the features of the invention relates to forming the brake shoes with the slots for the anchor posts 36. Preferably, each of the shoes is formed with a central stiffening 70 web which is slotted at its end at 50 to permit the passage of the anchoring posts 36. Reinforcing plates 52 on opposite sides of this web are also slotted for the passage of the anchoring posts and are spot welded to 75 opposite sides of the web of the shoes, the reinforcing plates 52 having portions extending beyond the web and which are preferably unslotted. Thrust members 54 engaging the cam 20 have parts extending into 80 the space between the reinforcing plates 52 into engagement with the ends of the webs of the shoes, and preferably have laterally extending portions projecting across and engaging the ends of the reinforcing plates 52. Members 54 may be welded or otherwise secured to the shoes. 85

In the particular arrangement illustrated in the drawing, the idle positions of the shoes 14 are determined by stop devices 60 co-operating with an auxiliary return spring 62. As shown, the stop 60 comprises a stud 64, positioned on the backing plate and a strap 66 pivotally connected by one end to the stud 64 and having a bolt 68 in the other end thereof engaging a slot 70 in the web of the shoe. These devices may be any desired form, as may also the adjustable joint 16, and they are therefore not described herein in detail. 90

While one illustrative embodiment of the 100

invention has been described in detail, it is not my intention to limit its scope to that particular embodiment or otherwise than by the terms of the appended claims.

5 I claim:

1. A brake comprising, in combination, a drum, a backing plate at the open side of the drum, a friction device in the drum having adjacent separable ends and formed with 10 slots in said ends, a shaft passing through the backing plate and having an applying device acting on said ends, supporting means adjacent the backing plate and in which the shaft is journaled, and devices on opposite 15 sides of the shaft and securing said means to the backing plate and which extend through the slots in the ends of the friction device and one of which serves as an anchor for the friction device when the drum is 20 turning in one direction and the other of which serves as an anchor for the friction device when the drum is turning in the other direction.

2. A brake comprising, in combination, a 25 drum, a backing plate at the open side of the drum, a floating friction device in the drum having adjacent separable ends and formed with slots in said ends, a shaft passing through the backing plate and having an 30 applying device acting on said ends, supporting means adjacent the backing plate and in which the shaft is journaled, and devices on opposite sides of the shaft and securing said means to the backing plate and which extend 35 through the slots in the ends of the friction device and against one of which devices the friction device anchors when the drum is turning in one direction and against the other of which devices the friction device anchors 40 when the drum is turning in the other direction.

3. A brake comprising, in combination, a shoe formed with a slot, a post shouldered to 45 form a portion of reduced diameter passing through said slot, a washer resting against the shoulder of said post and engaging one side of the shoe, and another washer carried by the reduced-diameter portion of the post and held against movement lengthwise 50 of the post and engaging the opposite side of the shoe.

4. A brake shoe having a stiffening web formed with a slot extending inwardly from 55 its end, slotted reinforcing plates secured on opposite sides of said web and having unslotted portions extending beyond the end of said web, and a thrust member extending between said portions of the reinforcing plates engaging the end of the web and abutting the reinforcing plates.

5. A brake shoe having a stiffening web, reinforcing plates secured on opposite sides of said web and extending beyond the end of 60 said web, and a thrust member extending

between said portions of the reinforcing plates and abutting the end of the web.

6. A brake shoe having a stiffening web formed with a slot extending inwardly from its end, slotted reinforcing plates secured 70 on opposite sides of said web and having unslotted portions extending beyond the end of said web, and a thrust member extending between said portions of the reinforcing plates in line with said web, said thrust member engaging the web and abutting the extending portions of the reinforcing plates. 75

7. A brake shoe having a stiffening web, reinforcing plates secured on opposite sides of said web and having portions extending 80 beyond the end of said web, and a thrust member extending between said portions of the reinforcing plates in line with said web and projecting laterally across the ends of the reinforcing plates. 85

8. A brake comprising, in combination, a drum, a backing plate at the open side of the drum, a floating friction device in the drum having adjacent separable ends, a shaft passing through the backing plate and having an 20 applying device acting on said ends, supporting means adjacent the backing plate and in which said shaft is journaled, and a pair of anchorage devices securing the supporting means to the backing plate on opposite sides of the shaft and on one of which one of said ends anchors when the drum is turning in one direction and on the other of which the other of said ends anchors when the drum is turning in the other direction. 95

9. A brake, comprising, in combination, a drum, a backing plate at the open side of the drum, a floating friction device in the drum having adjacent separable ends, a shaft passing through the backing plate and having an applying device acting on said ends, supporting means adjacent the backing plate and in which said shaft is journaled and which holds the shaft against shifting, and anchorage means securing the supporting means to the backing plate and on which one of said ends anchors when the drum is turning in one direction and on which the other of said ends anchors when the drum is turning in the other direction. 110

10. A brake backing plate having reinforcing parts provided with a bearing for an operating shaft, in combination with a pair of anchor members extending through the backing plate on opposite sides of the bearing and having collars on the inner side of the plate and nuts threaded on their ends and co-operating with the collars to clamp said parts to the backing plate. 115

11. A brake comprising, in combination, a 120 drum, a support, a plurality of floating connected shoes within the drum, applying means for said shoes including a shaft extending crosswise of said support, a bearing device in which said shaft is journaled, and 125 130

a pair of anchors securing the bearing device to said support and against one of which one of said shoes anchors when the drum is turning in one direction and against the other of which a different one of said shoes anchors when the drum is turning in the other direction.

12. A brake comprising, in combination, a drum, a support, a plurality of floating connected shoes within the drum, applying means for said shoes including a shaft extending crosswise of said support, a bearing device in which said shaft is journaled, and anchorage means securing the bearing device to said support and against which one of said shoes anchors when the drum is turning in one direction and against which a different one of said shoes anchors when the drum is turning in the other direction.

13. A brake backing plate having a shaft bearing secured thereto by a pair of spaced brake anchors.

14. A brake backing plate having a shaft bearing fixedly secured thereto by a brake anchorage means.

15. A brake backing plate having reinforcing plates arranged flat against its inner and outer faces and provided with a shaft bearing, in combination with brake anchors on opposite sides of said bearing securing the reinforcing plates to the backing plate.

16. A brake backing plate having reinforcing plates arranged flat against its inner and outer faces and provided with a shaft bearing, in combination with brake anchorage means securing the reinforcing plates to the backing plate.

17. A brake backing plate having mounted thereon a shaft bearing including a part resting flat against the plate, in combination with brake anchors on opposite sides of said bearing and securing said part to the backing plate.

18. A brake backing plate having mounted thereon a shaft bearing including a part resting flat against the plate, in combination with brake anchorage means fixedly securing said part to the backing plate.

19. A brake backing plate having a shaft bearing with laterally-extending portions resting against the plate, in combination with brake anchors passing through said plate and said portions and having collars and nuts threaded on their ends and cooperating with the collars to bolt the plate and the shaft bearing together.

In testimony whereof, I have hereunto signed my name.

LUDGER E. LA BRIE.
